Specification for Design.

Patented Oct. 18, 1921.

Application filed August 31, 1920. Serial No. 407,270. Term of patent $3\frac{1}{2}$ years.

To all whom it may concern:

Be it known that I, RALPH D. PARKER, a citizen of the United States, residing at San Francisco, in the county of San Francisco and State of California, have invented a new, original, and ornamental Design for a Windshield-Wing, of which the following is a specification, reference being had to the accompanying drawing, forming part thereof.

Figure 1 is a perspective view of a wind shield wing, showing my new design, and Fig. 2 is an end view thereof.

I claim:

The ornamental design for a windshield wing, as shown.

RALPH D. PARKER.
